UNITED STATES PATENT OFFICE.

CHARLES A. SMITH, OF PHILADELPHIA, PENNSYLVANIA.

PENCIL.

Application filed June 3, 1926. Serial No. 113,375.

- My invention relates to new and useful improvements in pencils, and more particularly to that class of pencils known as automatic ones, and has for its primary object 5 to improve and simplify the construction thereof so as to provide a closure which will be inexpensive in the cost of manufacture, although strong and durable and effective in operation.
- 10 Another object of the invention is to so construct the barrel of the pencil as to provide a square bore so that any one of the four corners may receive a projection from the lead holder to prevent rotation thereof.
- 15 A further object of the invention is to provide a helical coil propelling element constructed from untempered iron or similar material so as to prevent lengthwise springing thereof.
- 20 A still further object of the invention is to provide a pencil sharpener in conjunction with the other parts so that should the point of the lead break off, it may be resharpened.
- 25 Another object of the invention is to provide a simple and unique means for replacing one lead with another.

With these and other ends in view, this invention consists in the details of construction and combination of elements herein-after set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1, is a longitudinal sectional view of 40 a pencil constructed in accordance with my invention with portions left in elevation to illustrate certain details of construction.

Fig. 2, is a transverse sectional view of the barrel.

Fig. 3, is a section on the line 3—3 of Fig. 1.

Fig. 4, is an end view of the lead holder.

Fig. 5, is a side elevation thereof.

Fig. 6, is an end view of the pencil sharpener.

Fig. 7, is a side elevation of the same.

In carrying out my invention as herein embodied, 10 represents the barrel of a pencil which may be constructed of wood, metal or other suitable material, and so fashioned as to provide a bore 11, square

in cross section, thereby providing four corners, in any one of which will slide the lug 12, projecting from the lead holder 13. By constructing the barrel in this manner, it is 60 unnecessary to position the lead holder in any one particular position.

The lead holder is preferably made from a longitudinally split tube, thereby providing a gripping end 14 to receive and hold 65 the lead 15, while above the gripping portion, two sections of the metal are partially cut from the lead holder and bent inward to provide two spring stops 16, the free ends of which overlie the upper end of said gripping portion and engage an end of the lead to prevent the same from being pushed inward.

The lead holder is longitudinally movable within the helical actuator 17, which is 70 coiled from the untempered strip of ribbon or iron or other suitable metal so as to have practically no longitudinal flexibility, and the coils of this actuator provide a convolute slot 18 into which projects the lug 12 of the 75 lead carrier, and when the actuator is revolved, said lead carrier will be moved longitudinally thereof. The actuator is located within the bore of the barrel, and has its upper end secured to a collar 19 revolvably 80 mounted in the upper end of said barrel, and secured against endwise movement in any well-known manner, as for instance, the end of the barrel may be turned into a groove 85 in the collar.

By eliminating or reducing to a minimum any flexibility in the actuator, the lead when in use is held substantially as firm as when fixed in the body of the pencil.

In order to revolve the collar, I provide 90 a cap 20 having spring prongs 21 which will frictionally grip the collar when the cap is placed thereon, and the exterior of said cap may be knurled, as at 22 to assist the user firmly grasping said cap. Projecting inwardly from the center of the top wall of the cap is a pencil sharpener 23, which has a longitudinal slot 24 so that a blade 25 may be formed from one edge, while the slot permits the passage of the 100 particles of material removed from the lead being sharpened, and from the inner end of the sharpener projects a pusher 26 to engage a lead for pushing it into the lead holder.

When it is desirable to remove a lead 110 and replace it by another, the parts are actuated until the lead holder 13 is moved up

to the top of the pencil, and after the removal of the cap, a new lead may be inserted in the upper end of the pencil and projected into the lead holder forcing out the 5 stub of the old one, if such stub remains. The new lead is pushed in as far as possible, and then the pusher 26 is brought into engagement with the upper end of said lead and the latter may then be pushed inward 10 until its end passes the free ends of the spring tongues 16 which will occur just as the cap is brought into its operative position. The pencil is now ready for use, and by revolving the cap in the proper direction 15 the lead holder will be moved downwardly until said lead projects the desired distance from the lower end of the pencil, and said lower end of the pencil may be tapered, as indicated at 27. Should the point of the 20 lead break off, it may be re-sharpened by removing the cap and forcing the latter over the projecting end of the lead until the latter enters the sharpener, and then by revolving the sharpener in the usual manner, 25 the desired point will be formed upon the lead.

By making the actuator of untempered iron it has practically no longitudinal flexibility, therefore the lead will not be forced 30 back into the pencil barrel during writing operations.

Because of the square bore in the barrel of the pencil, the assembling operations may 35 be quickly accomplished for when the parts are inserted in the barrel, it requires less than a quarter of a turn in one direction or the other to bring the lug 12 into registration with one of the corners.

Of course I do not wish to be limited to 40 the exact details of construction as herein shown as these may be varied within the limits of the appended claims without departing from the spirit of my invention.

Having thus fully described my invention, what I claim as new and useful is:

1. A pencil comprising a barrel having 45 a bore square in cross section; a helical ac-

tuator revolvably mounted within the bore of said barrel; a lead holder within the actuator; means carried by said holder for cooperation with the actuator to move the lead holder longitudinally, said means also engaging one of the corners of the bore to prevent rotation of said lead holder; means to prevent retrograde movement of a lead 55 relative to the holder after being relatively positioned; a collar connected with the actuator for revolving the latter; and a cap removably mounted upon the collar; said cap being so constructed that when removed, 60 it can be used as a pencil sharpener.

2. A pencil including a barrel open at both ends; a lead holder within the barrel, also open at both ends to permit insertion of a lead through the upper end of the barrel 65 into the lead holder; means on said lead holder to prevent upward movement of the lead after being operatively positioned; means to prevent rotation of the lead holder; and means to move said lead holder longitudinally within the barrel. 70

3. A pencil including a barrel open at both ends; a lead holder within the barrel, also open at both ends to permit insertion of a lead through the upper end of the barrel 75 into the lead holder; means on said lead holder to prevent upward movement of the lead after being operatively positioned; means to prevent rotation of the lead holder; means to move said lead holder longitudinally within the barrel; a collar connected with the means for moving the lead holder; a cap removably mounted upon the collar; said cap being so constructed that when removed it can be used as a pencil 80 sharpener; and a pusher depending from the inner end of the cap for engagement with a lead to push the same through the lead holder when the latter is in its uppermost position. 85

In testimony whereof, I have hereunto affixed my signature.

CHARLES A. SMITH.
